(57) **CLAIM**

The ornamental design for a handle for beauty tool, as shown and described.

DESCRIPTION

FIG. 1 is a front perspective view of a handle for beauty tool, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view thereof, shown in a first environment of use; and,

FIG. 9 is a front perspective view thereof, shown in a second environment of use.

In the drawings, the broken lines illustrate portions of the article and form no part of the claimed design. The additional broken lines shown in FIGS. 8 and 9 illustrate environmental subject matter and form no part of the claimed design.

1 Claim, 8 Drawing Sheets
